UNITED STATES PATENT OFFICE.

THOMAS W. KENWORTHY, OF RICHLAND, IOWA.

ROD-COUPLING.

SPECIFICATION forming part of Letters Patent No. 739,548, dated September 22, 1903.

Application filed March 6, 1903. Serial No. 146,515. (No model.)

To all whom it may concern:

Be it known that I, THOMAS W. KENWORTHY, a citizen of the United States, residing at Richland, in the county of Keokuk and State of Iowa, have invented certain new and useful Improvements in Rod-Couplings, of which the following is a specification.

In the operation of windmills it is desirable at times to disconnect the pump from the wind-engine either to permit manual operation of the pump or for other cause.

This invention provides a simple and effective means to admit of the coupling and uncoupling of the pump-rod from the mill at a moment's notice, same consisting, essentially, of a lock-pin slidably mounted in a peculiar manner and a cam-lever co-operating therewith for moving the lock-pin in and out and holding it in place in either position.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a rod-coupling embodying the invention. Fig. 2 is a longitudinal section showing the relation of the parts when the pump-rod is released. Fig. 3 is a view similar to Fig. 2, showing the position of the parts when the pump-rod is coupled.

Corresponding and like parts are referred to in the following description and indicated in all the views of the drawings by the same reference characters.

The pump-rod is indicated at 1 and the rod from the windmill at 2. A box 3 is secured to an end of one of the rods, preferably to the mill-rod 2, and consists of a casting adapted to receive the end of pump-rod 1, same being secured thereto by a lock-pin 4, slidably mounted in an offstanding lug 5, provided at a side of box 3. Openings are formed in opposite sides of box 3 in coincident relation for reception of end portions of lock-pin 4, so as to support same at opposite sides of rod 1.

The inner end of lock-pin 4 is made rounding and its outer end is enlarged to form a head 6 of angular formation and provided at its upper side with cam-notch 7. The lug 5 is preferably an integral part of casting or box 3, and its upper side is grooved to form a seat in which head 6 of lock-pin 4 is slidably mounted.

An operating-lever 8 co-operates with lock-pin 4 to effect a sliding movement thereof in each direction and is pivotally connected to box or casting 3, being mounted upon bearing 9, projected laterally from said box, and having a threaded opening to receive a machine-screw or like fastening 10, by means of which operating-lever 8 is held in place upon the bearing and is adapted to be tightened, so as to compensate for wear and prevent a too free movement of said operating-lever. The pivotal end of the operating-lever is circularly enlarged and provided with a cam 11, having interlocking connection with lock-pin 4 to effect sliding movement thereof as the operating-lever is turned upon its bearing. In the preferable construction the cam 11 is a fin or flange and enters cam-notch 7. The parts are so proportioned that when lever 8 is thrown to one side the lock-pin 4 is moved outward and when thrown to the opposite side said lock-pin is moved inward. The operating-lever is limited in its movement in each direction by contact with lug 5. The weight of the outer end of lever 8 is sufficient to hold it in the required position and prevent casual displacement of lock-pin 4.

The coupling is susceptible of use wherever it may be required to connect two rods or like parts, and the rod to be inserted in box 3 is apertured to receive lock-pin 4 and when inserted into said box is secured by operating-lever 8 to project lock-pin 4 through the opening thereof. To release the rod coupled to part 3, lever 8 is thrown in the opposite direction, thereby withdrawing the lock-pin and permitting separation of the parts, as will be readily comprehended.

Having thus described the invention, what is claimed as new is—

1. In a rod-coupling, a slidably-mounted lock-pin, and an operating-lever provided with a spiral cam portion having interlocking connection with said lock-pin and adapted to

hold same in either extreme position, substantially as set forth.

2. In a coupling for rods, a slidably-mounted lock-pin provided with a notched head, 5 and an operating-lever having a spiral cam-flange coöperating with said notched head to effect sliding movement of the lock-pin, substantially as described.

3. In a rod-coupling, a connector provided 10 with an offstanding lug having a seat in a side, a lock-pin slidably mounted in said seat, and an operating-lever pivoted to said connector and having a spiral cam for coöperation with the lock - pin to effect a sliding movement 15 thereof, substantially as specified.

4. In a rod-coupling, a box having an off-standing lug provided in one side with a seat, a lock-pin adapted to be projected across said box and provided with a head slidably mounted 20 in the seat of said lug, and an operating-lever pivoted to said box and having a spiral

cam portion coöperating with the head of said lock-pin to effect sliding movement thereof, substantially as described.

5. The herein-described rod-coupling comprising a box having openings in opposite sides in coincident relation and having an off-standing lug provided in its upper side with a seat, a lock-pin having its outer edge notched and made angular and slidably mounted in 30 the seat of said lug, and an operating-lever provided with a spiral cam-flange for coöperation with the notched head of the lock-pin to effect sliding movement thereof, substantially as and for the purpose set forth. 35

In testimony whereof I affix my signature in presence of two witnesses.

THOMAS W. KENWORTHY. [L. S.]
